CLAIM

The ornamental design for a case, as shown and described.

DESCRIPTION

FIG. 1 is a top perspective view of a case, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a sectional view of 8-8 along the line in FIG. 2; and, FIG. 9 is a top perspective sectional view of 9-9 along the line in FIG. 2.

The dashed broken lines in the figures illustrate portions of the Case that form no part of the claimed design.

The short-short-long dashed broken lines immediately adjacent to the claimed areas in the views represent the boundaries of the design and form no part of the claimed design.
